UNITED STATES PATENT OFFICE

KENNETH S. JOHNSON, OF JERSEY CITY, NEW JERSEY, ASSIGNOR, BY MESNE ASSIGNMENTS, TO WESTERN ELECTRIC COMPANY, INCORPORATED, A CORPORATION OF NEW YORK

ELECTRICAL NETWORK

Application filed January 15, 1925. Serial No. 2,482.

This invention relates to electric wave transmission, and more particularly to artificial lines such as are used to increase the time of propagation of an electric wave between the terminals of a transmission line.

An object of the invention is to effect a uniform retardation of waves having a wide range of frequencies.

The propagation of waves in a homogeneous medium or along uniform lines of negligible resistance takes place with a velocity that is constant for all wave frequencies. If, however, the medium or the line comprises a connected system of discrete massive and elastic elements, the wave velocity is no longer constant but is dependent upon the wave frequency.

Well known examples of media of the latter type are coil loaded telephone lines, and wave filters of the type disclosed in U. S. patent to G. A. Campbell, No. 1,227,113 issued May 22, 1917.

The propagation velocity of waves along uniform lines may, in accordance with well known principles, be reduced by increasing the distributed inductance and capacity of the line. Such lines could be used as delay circuits but their cost and size render them impracticable. For this reason an artificial line comprising simple inductive and simple capacitive elements has been preferred despite the difficulty of obtaining uniform wave velocity therein.

By the application of the present invention artificial lines may be constructed in which, so far as applicant is aware, the uniformity of the propagation velocity is much greater than it has hitherto been possible to obtain.

A feature of the lines, or delay circuits, constructed in accordance with the invention is the combination of networks which produce velocity irregularities of opposite types whereby the irregularity due to one network is neutralized by that due to others.

The nature of the invention will be more

fully understood from the detailed description which follows:

Of the accompanying drawings,

Fig. 1 shows in schematic form one unit of an artificial line embodying the invention; 50

Fig. 2 is a group of curves illustrating the operation of the invention;

Fig. 3 shows, partly diagrammatically and partly schematically, a system in which the invention is usefully applied; 55

Figs. 4 and 5 show schematically additional forms of network embodying the invention;

Fig. 6 shows an equivalent form of part of the network of Fig. 5; and 60

Fig. 7 shows in graphic representation certain impedance characteristics relating to the operation of the invention.

The propagation of waves in an electrical line comprising a connected sequence of four-terminal networks is controlled by factors which broadly fall into two classes. The first class comprises the self-characteristics of the individual sections, or, the properties they possess by virtue of their own dimensions and configuration. The second class comprises those factors which are present only as the result of the interconnection of the sections. 70

The properties of a line comprising an infinite number of equal symmetrical networks have been extensively studied and it is well known that they are dependent only upon the self-properties of the individual networks. For example, if in an infinitely extended line the electromotive force at the terminals of one network of the sequence be denoted by E then the current I_N leaving the Nth succeeding network in the direction of propagation is expressed by the following 80 equation:

$$I_N = \left(\frac{E}{Z_k} \cdot e^{-NP} \right) \quad (1)$$

in which Z_k and P are respectively the itera- 90

tive impedance and the propagation constant of each of the similar networks.

The impedance Z_k and the constant P depend only upon the dimensions and configuration of the networks; they may be determined by simple measurements upon the complete network by itself or they may be computed from the dimensions of the elements forming the structure.

10 In a finite line comprising terminal impedances and an intervening sequence of dissimilar networks, factors of the second class also enter into the wave propagation. The received current at one end of the line corresponding to an electromagnetic force, E , acting at the other end may be expressed by the equation:

$$I_R = \frac{E}{2\sqrt{Z_R Z_S}} (e^{-\Sigma P})(e^{-\Sigma L}) \quad (2)$$

20 In this equation I_R is the received current, Z_S and Z_R are the terminating impedances at the sending and receiving ends respectively, ΣP is the sum of the propagation constants of the individual sections and ΣL is the sum of various terms which take into account the inequalities of the impedances of the two parts of the line brought together at the junctions of the sections.

30 By the choice of sections having iterative impedances substantially equal over a wide range of frequencies and substantially equal to the terminating impedances of the line, the factor $e^{-\Sigma L}$ is reduced to a negligibly small quantity and the factor $e^{-\Sigma P}$ becomes the dominating factor in the transmission.

40 The propagation constant P of each section being in general a complex quantity, the equation for the received current in this simplified case may be written

$$I_R = \frac{E}{2\sqrt{Z_R Z_S}} (e^{-\Sigma D})(e^{-\Sigma j\beta}) \quad (3)$$

45 in which ΣD is the sum of the real components of ΣP and $\Sigma j\beta$ is the sum of the imaginary components. This equation states that I_R is related to a current having the value

$$I_0 = \frac{E}{2\sqrt{Z_R Z_S}} \quad (4)$$

50 by a diminution constant ΣD , and by a phase constant $\Sigma \beta$, the former being a measure of the relative magnitude of the currents I_0 and I_R and the latter of their relative phases. In practice both terminal impedances, Z_R and Z_S , are made non-reactive and the component sections have iterative impedances that are 55 non-reactive throughout the important frequency range. The input current is consequently in phase with the electromotive force and the received current I_R differs in phase from the input current or from the input 60 E. M. F. by the angle $\Sigma \beta$.

The angle $\Sigma \beta$ provides a measure of the time taken for a current wave to traverse the line, the magnitude of the time interval t being given by the equation

$$t = \frac{\Sigma \beta}{2\pi f}, \quad (5)$$

in which f denotes the wave frequency.

The quantity V given by the equation

$$V = \frac{2\pi f N}{\Sigma \beta} \quad (6)$$

in which N denotes the number of sections 80 constituting the line, expresses the average 85 number of sections traversed by a wave in unit time and so corresponds to the average propagation velocity through the system. In an artificial line there is no proper space 90 distribution whereby the velocity may be expressed in the ordinary manner as so many meters per second, but the concept of the velocity as here defined, in terms of the sections as equivalent space units, is nevertheless of 95 great utility and convenience.

To obtain a constant velocity, or a constant propagation time, it is necessary that the phase constant $\Sigma \beta$ should increase in direct proportion to the frequency. In other 95 words, the angular components of the propagation constants of the individual networks should add together to a sum that is directly proportional to the wave frequency.

In this specification the term "phase-constant" is used to denote the imaginary, or angular, term of the propagation constant of a network; the variation of the phase-constant with respect to the wave frequency is termed the "phase-characteristic"; and the multiplying factor by which the phase-constant is related to the frequency is termed the "phase-factor".

One combination of networks for which this relationship holds over a wide frequency range is shown in Fig. 1. It comprises two sections S_1 of a simple low-pass filter of the Campbell type having series inductance and shunt capacity and a third section S_2 comprising series inductances and diagonally cross connected shunt capacities. The inductance of a full series branch of the low-pass filter sections is denoted by L and the shunt capacity by C ; these values being indicated in the figure. These sections are 115 terminated at the middle of a series branch, or as it is generally termed at mid-series, the individual coils having inductances equal to 120

$$\frac{L}{2}.$$

125 The inductances of the section S_2 are related to those of the filter section by a numerical factor a and the shunt capacities to 130

the filter shunt capacities by a second factor

$$\frac{1}{2b}.$$

To distinguish between the two types of network the term "ladder" has been used to define a network of the simple series-shunt type, and the term "lattice" to define the diagonally cross connected type, of which the section S_2 is an example. The terms are used in the present specification in the senses indicated.

For an analysis of the characteristics of these networks and for the principal formulae relating to their propagation constants reference is made to an article by G. A. Campbell, The physical theory of the electric wave filter, printed in the Bell System Technical Journal, volume 1, No. 2, November, 1922.

The propagation constant of each section of either type of network is a function of the ratio of the total series impedance to the total shunt impedance. In the mid-series terminated low-pass filter sections of Fig. 1, each series arm furnishes one half of the full series impedance. In the lattice section, the full series impedance is divided equally between the two lines and the total shunt impedance is that of the two diagonal branches connected in multiple.

The propagation constant of one section of a ladder network is given by the following general formula:

$$P = 2 \tanh^{-1} \frac{\frac{\gamma}{2}}{\sqrt{1 + \frac{\gamma^2}{4}}} \quad (7)$$

in which γ^2 denotes the ratio of the series impedance to the shunt impedance.

For a lattice network the propagation constant is expressed by

$$P_L = 2 \tanh^{-1} \frac{\gamma_L}{2} \quad (8)$$

The subscript L being used to distinguish the co-efficients of the lattice network from those of the ladder network.

If the ladder network is composed of reactive elements the propagation constant determined by Formula (7) may be either real or imaginary depending upon the value of γ but it cannot be complex. It will be imaginary for all frequencies at which $\frac{\gamma^2}{4}$ is negative and less than unity, and real for all other values. This signifies that the wave propagation through such a network, or through a continued sequence of them constituting a wave filter, is characterized either by a modification of the wave intensity without change of phase, thus defining the at-

uation range or by a progressive change of phase without attenuation of the wave.

The propagation constant of the lattice section of Fig. 1 is imaginary for all values of the frequency. The section therefore produces only a phase change in the transmitted waves, which are propagated at all frequencies without attenuation.

The phase characteristics of the component networks of Fig. 1 are shown in Fig. 2 along with the resultant phase characteristic of the combination. The abscissæ are proportional to the ratio, denoted by α , of the wave frequency f to the cut-off frequency f_c of the low pass filter sections; the ordinates represent the phase angles in degrees.

The curve OA represents the phase characteristic of the two ladder sections together and the curve OB the phase characteristic of the lattice network. The ordinates of curve OC are equal to half the sum of the ordinates of the other two curves, or to half the resultant phase angles of the combination. The curves OA and OB are curved in opposite senses and for a range of frequencies extending from zero to about seven-tenths of the cut-off frequency the departure from linearity of the one curve is just sufficient to neutralize the departure of the other curve. Up to this point the curve OC is practically straight, indicating that all waves of lower frequency are propagated through the combined network with a uniform velocity.

The accuracy of the compensation may be examined more fully by determining and comparing explicit formulæ for the phase-constants of each type of network.

By well known mathematical processes formulæ 7 and 8 may be expanded into the following infinite series, which apply within the transmission range,

$$\left. \begin{aligned} P &= \gamma - \frac{1}{24} \gamma^3 + \frac{3}{640} \gamma^5 - \frac{5}{7168} \gamma^7 + \\ P_L &= \gamma_L + \frac{1}{12} \gamma_L^3 + \frac{1}{80} \gamma_L^5 + \frac{1}{448} \gamma_L^7 + \end{aligned} \right\} \quad (9)$$

The ratios γ and γ_L may be expressed in terms of the constants of the structural elements and the wave frequency; for the structures of Fig. 1 they are

$$\left. \begin{aligned} \gamma &= j 2\pi f \sqrt{LC} \\ \text{and} \quad \gamma_L &= j 2\pi f \sqrt{\frac{a}{b} LC} = \sqrt{\frac{a}{b} \gamma} \end{aligned} \right\} \quad (10)$$

Further, since the cut-off frequency of the ladder filter sections is defined by

$$f_c = \frac{1}{\pi \sqrt{LC}} \quad (11)$$

it follows that

$$\gamma = 2j \frac{f}{f_c} = 2jx \quad (12)$$

The real parts of P and P_L are zero throughout the transmission range and the imaginary parts, or the phase constants β and β_L , are respectively

$$\beta = 2x + \frac{1}{3}x^3 + \frac{3}{20}x^5 + \frac{5}{56}x^7 + \quad \left. \right\} \quad (13)$$

and

$$\beta_L = 2dx - \frac{2}{3}d^3x^3 + \frac{2}{5}d^5x^5 - \frac{2}{7}d^7x^7 + \quad \left. \right\} \quad (13)$$

the quantity

$$\sqrt{\frac{a}{b}},$$

which by Equations (10) expresses the relationship between γ and γ_L , being written as d for convenience.

The combination of two ladder sections with one lattice section has a resultant phase constant

$$\beta_1 = 2\beta + \beta_L = \left. \left. \begin{aligned} & 2\left((2+d)x + \frac{1}{3}(1-d^3)x^3 + \frac{1}{20}(3+4d^5)x^5 + \right) \end{aligned} \right\} \quad (14) \right.$$

from which the term involving x^3 disappears when d is equal to unity.

The straightening out of the phase-constant characteristic is due to the elimination of this third power frequency variation, the terms of the series involving higher powers of x being negligibly small for the frequencies considered.

Other combinations of lattice and simple ladder networks may be designed to produce the same result. For example, the unit combination network may comprise one network of each kind, or two lattice and one ladder network, or again one lattice network and one half section of the ladder type. Appropriate values of d may be determined, which in each case reduce the resultant third power variation to zero. For the additional examples cited the proper values of d are respectively

$$\frac{1}{\sqrt{2}}, \text{ and } \frac{1}{\sqrt{4}},$$

the latter value applying to both of the last two combinations mentioned above, which are essentially similar. The combination of one lattice and one half ladder section corresponds to the part of Fig. 1 between the dotted lines AA' and BB'.

Combination units of the aforementioned types may be joined together to form an artificial line in which the phase constant has the same uniformity as in the individual sections and in which the retardation time is proportional to the number of units in the line. By the use of a sufficient number of units the retardation time may be adjusted to any value and variable lines may be made by the addition of switching means for cutting out or inserting the individual units.

To preserve the uniformity of velocity obtained by the combinations it is necessary that the iterative impedances of the successive sections should, throughout the range of frequencies to be utilized, be alike as nearly as possible and should be substantially equal to the impedance of the terminal apparatus or of the lines to which the artificial line may be connected.

The iterative impedance, denoted by K_L , of a lattice network of the type under consideration is constant and non-reactive at all frequencies. In terms of the co-efficients indicated in Fig. 1 it is

$$K_L = (\sqrt{ab}) \left(\sqrt{\frac{L}{C}} \right) \quad (15)$$

The iterative impedance, denoted by K of the mid-series terminated filter sections is a variable quantity. At zero frequency it has the value

$$K_0 = \sqrt{\frac{L}{C}} \quad (16)$$

and at higher frequencies it diminishes continuously to zero at the cut-off frequency. The variation with frequency is expressed by the equation

$$\frac{K}{K_0} = \sqrt{1 - x^2}, \quad (17)$$

and is illustrated by the curve G of Fig. 7 in which the ratio

$$\frac{K}{K_0}$$

is plotted as a function of x .

The combination network of Fig. 1 has a linear phase characteristic through a range of frequencies corresponding to values of x between zero and 0.7. In the foregoing analysis, which indicates that this linearity is principally due to the elimination of the third power frequency variation, the effect of the difference between the iterative impedances of the networks is ignored. Detail calculations show that if the iterative impedance of the lattice network is made equal to the initial iterative impedance of the ladder network, that is, to the impedance corresponding to zero frequency, the disparity of the iterative impedances throughout the range of x from zero to 0.8 does not affect the phase constant by more than one part in five hundred.

The disparity of the impedances may be made less by proportioning the lattice network so that the iterative impedance is somewhat less than the initial iterative impedance of the ladder network. If, for example, it is made equal to 0.8 of the initial impedance of the ladder network the disparity at eight-tenths of the cut-off frequency will be reduced by half and the effect upon the phase constant

70

75

80

90

95

100

110

115

125

130

will be diminished correspondingly at all frequencies greater than 0.4 of the cut-off frequency.

It was shown in an earlier part of the specification that the elimination of the third power frequency variations fixed the value of the co-efficient d and thereby determined by means of Equations (10) the relationship between the impedance ratio γ and γ_L of the component networks. The individual impedances may be varied without changing the values of the impedance ratios and may be chosen to give the networks any desired iterative impedance. The selection of a definite value for the iterative impedance determines the proportions of the component networks in relation to each other; the numerical values of the individual inductances and capacities are finally determined by the specification of the frequency range through which compensation is desired.

As an example, the design of a network of the three section type shown in Fig. 1 may be considered, the conditions being postulated that the network be suited for use in connection with a transmission line of 600 ohms impedance and that uniform velocity, or uniform delay, be obtained for all frequencies up to 3,000 c. p. s.

The network has a linear phase-characteristic up to 0.7 of the cut-off frequency; it is desirable therefore that the cut-off frequency should exceed 4,200 c. p. s. As a convenient value 5,000 c. p. s. may be chosen.

Inserting the value of the cut-off frequency in Equation (11) gives

$$LC = 0.00405 \times 10^{-6} \quad (18)$$

The iterative impedance of the lattice sections, being uniform, should be made equal to the line impedance or 600 ohms, and, to minimize reflection losses most effectually, should be equal to 0.8 of the initial iterative impedance of the ladder section.

Inserting these values in Equations (15) and (16) gives

$$\sqrt{\frac{L}{C}} = 750 \text{ ohms} \quad (19)$$

and

$$a \cdot b = 0.64 \text{ numeric} \quad (20)$$

The condition that the third power frequency variation be eliminated requires in accordance with Equation 14, that the factor d be unity, or,

$$\frac{a}{b} = 1 \quad (21)$$

The final solution of Equations (18) to (21) gives the numerical values of L , C , a , and b , as follows:

$$\begin{aligned} L &= .048 \text{ henrys} \\ C &= .085 \text{ microfarads} \\ a &= b = 0.8 \end{aligned}$$

The retardation time of one network of this type as obtained from Equations (5) and (14) is

$$t = 3.82 \times 10^{-4} \text{ seconds.}$$

In Figs. 4 and 5 are shown composite networks which include filter sections other than the simple low pass type hereinbefore considered. In Fig. 4 the ladder section comprises an anti-resonant circuit in the series branch and a simple capacity in the shunt branch, and in Fig. 5 the series branches include inductances mutually coupled together, the sense of the coupling being such that the mutual inductance increases the total inductance of the series branches.

Filter sections of these types are fully considered in a paper by O. J. Zobel, Theory and design of uniform and composite electric wave filters, printed in the Bell System Technical Journal, Vol. II, No. 1, January, 1923. In the paper referred to they are termed M-type wave filters and are divided into two classes, "mid-shunt", and "mid-series", which are defined by the properties of their respective iterative impedances. The properties of these filters are related by the formulæ given by Zobel to the properties of certain of the Campbell type filters which have the unique property that the product of the series and the shunt branch impedances is constant.

The simple low pass filter sections of Fig. 1 are examples of this type to which the term "constant-k" has been applied by Zobel. The "mid-shunt" M-type sections are so defined because they have the same mid-shunt iterative impedance as the "constant-k" section to which they are related. A corresponding relationship holds in connection with the "mid-series" M-type sections.

The ladder type filter section of Fig. 4 is of the mid-shunt M-type. It has the same initial iterative impedance and the same cut-off frequency as the simple low pass filter sections of Fig. 1 provided that the co-efficients of the elements are related to the inductance L and the capacity C of the simple filter by certain numerical factors, the values of which are defined as follows. The series inductance and the shunt capacity of the M-type filter sections are equal to the corresponding co-efficients of the simple filter section multiplied by a factor m which is a simple numeric and which may have any positive value between zero and unity. The capacity of the full series branch is related to the shunt capacity of the simple filter by the factor

$$\frac{1-m^2}{4m}.$$

These relationships are indicated in Fig. 4.

It is found that a simple relationship exists between the propagation constant of an

M-type filter section and the propagation constant of the corresponding "constant- k " filter. This is expressed by the following equation

$$5 \quad \tanh \frac{P_m}{2} = m \tanh \frac{P_k}{2} \quad (22)$$

in which P_m and P_k are respectively the propagation constants of the M-type and the corresponding "constant- k " sections.

10 The value of the propagation constant of a "constant- k " filter is given by Equation (7) by means of which Equation (22) may be transformed to

$$15 \quad P_m = 2 \tanh^{-1} \sqrt{\frac{m \gamma_k}{1 + \frac{\gamma_k^2}{4}}} \quad (23)$$

20 in which the subscript k denotes that the ratio γ refers to the "constant- k " filter. This equation gives the propagation constant of any M-type filter in term of the co-efficients of the simple Campbell, or, "constant- k " type.

25 In the case of a low pass filter, the right hand side of Equation (23) may be expanded into an infinite series which when expressed by means of Equation (12) in terms of x instead of γ contains only imaginary terms and therefore expresses the value of the phase-constant. The first three terms of the series are

$$30 \quad \beta_m = 2mx + \left(m - \frac{2}{3}m^3 \right)x^3 + \left(\frac{3}{4}m - m^3 + \frac{2}{5}m^5 \right)x^5 \quad (24)$$

40 By means of Equations (24) and (13) the necessary condition is determined for the elimination of the third power frequency variation in a network comprising both lattice sections and M-type sections.

45 If the network is of the form shown in Fig. 4, namely two lattice and one ladder section, the necessary condition is

$$50 \quad \frac{4}{3}d^3 = m - \frac{2}{3}m^3. \quad (25)$$

It is evident that this equation may be satisfied by a multiplicity of values of m and d , and that an additional condition must be fixed before a single solution can be found.

55 A useful feature of the M-type filter sections, which has been pointed out by Zobel in the aforementioned reference, is that one of the mid-section iterative impedances is, for values of m around 0.6, exceptionally constant throughout the transmission range. In a mid-shunt M-type section it is the mid-series iterative impedance that possesses this property, and in a mid-series type section it is the mid-shunt iterative impedance.

60 The curve H of Fig. 7 illustrates the varia-

tion of the mid-series iterative impedance of the M-type section of Fig. 4, when the co-efficient m has the value 0.6. The ordinates of the curve represent the ratios of the iterative impedance to its initial value and the abscissæ are proportional to the frequency ratio x . At zero frequency the iterative impedance has the same value as that of the simple low pass filter and this value is maintained with great uniformity up to a value of x equal to 0.85.

70 Fixing the value of m makes Equation (25) determinate and gives a solution for the factor d upon which depend the constants of the lattice structure. The choice of the particular value 0.6 enables the ladder section to be designed so that there will be practically no disparity of the iterative impedances and consequently no reflection effects to impair the uniformity of the wave 75 velocity.

75 Under this condition the value of d for the combination shown in Fig. 4 is found to be

$$80 \quad d = 0.7$$

85 The actual values of the elements may be determined for any particular case in accordance with the procedure already described.

90 A composite network comprising one lattice and one mid-shunt M-type network may also be designed to have a substantially constant velocity characteristic. If the same value of m is used the value of d in this case is found to be

$$95 \quad d = 0.88$$

100 In Fig. 5 is illustrated a third type of composite network in which also the inventive idea is present. The section having coupled series arms is equivalent to the network illustrated in Fig. 6 when the sense of coupling is such that the mutual inductance increases the series arm inductances. It is a mid-series M-type section having properties related to those of the simple filter section with which it is associated provided that

$$105 \quad \left. \begin{aligned} L_1 + M &= m \left(\frac{L}{2} \right) \\ -M &= \frac{1-m^2}{4} L \\ C_2 &= mC \end{aligned} \right\} \quad (26)$$

110 It is evident that the second of these relationships can hold only when m has a value greater than unity.

115 A comparison of Equations (13) and (24) shows that the condition necessary for the elimination of the third power frequency variation of the phase constant in this combination is

$$120 \quad m - \frac{2}{3}m^3 = -\frac{1}{3} \quad (27)$$

the real root of which may be found by graphical methods to be

$$m=1.367$$

5 The proportions of L_1 , M_1 and C_2 follow from Equation (26).

10 The mid-series iterative impedance of the M-type section is the same as that of the simple filter section consequently there is no impedance disparity at the junction of the sections.

15 It should be noted that a single section of the coupled impedance type may by itself be made to have no third power frequency variation in its phase constant. The necessary condition is that

$$m - \frac{2}{3}m^3 = 0 \quad (28)$$

20 or

$$m=1.225$$

This value of m corresponds to a coupling factor of 0.2 between the half-series inductances L_1 .

25 The application of the invention in connection with a binaural system for determining the bearing of a source of sound waves is shown in Fig. 3.

30 An arrangement of this sort is described in Patent 1,628,992 to John Mills, dated May 17, 1927.

35 Use is made of the principle that sound waves arriving at the same instant upon the two ears of an observer appear to come from a source located directly before him.

40 Two microphones M_1 and M_2 spaced apart on a reference base line receive sound waves from the source to be located and translate them into electric waves which are transmitted through independent channels to the receivers T_1 and T_2 of an observer's head set. With each channel is associated a number of artificial line units, 2, which by means of switches, 1, may be inserted into or removed from the line as desired. The line units, which are indicated diagrammatically, are similar in construction throughout the system and may consist of composite networks of any of the types illustrated in Figs. 1, 4 and 5.

45 The microphones are supplied with current by the batteries 4 which are isolated from the other apparatus of the channels by transformer 3. The networks are designed in accordance with the foregoing principles to match the impedance of the receivers T_1 and T_2 and the transformers serve the additional purpose of transforming the microphone impedance to the same value.

50 Waves arriving from a direction making an angle θ to the direction normal to the base line arrive at the microphones at different instants separated by a time interval t which has the value

$$t = \frac{l \sin \theta}{V} \quad (29)$$

The distance between the microphones being denoted by l and the velocity of the waves by V . If the two channels were alike in their electrical lengths the waves would reach the telephone receivers at different instants and would give the observer the impression of a sound coming from a source located to one side of him. By inserting a sufficient number of line sections in one of the channels, which one depending upon the sense of the apparent bearing, binaural centering may be obtained in which the sound appears to come from a source squarely in front of the observer. The time t can be estimated by means of Equation (5) from the sum of the phase-factors of the line sections necessary to produce the binaural centering and hence by means of Equation (29) the bearing may be obtained.

55 The constant velocity property of the networks permits a calibration of the system to be made by which the bearing may be determined directly from the number of sections required for binaural centering and which is correct for waves of all important frequencies. A further advantage arising from this property is that all components of a complex tone are equally delayed and in consequence cannot produce any confusion of the binaural centering such as may occur when the component waves are unequally delayed.

60 Although the utility of the invention has been described in connection with a binaural direction finding system it is to be understood that it is not limited to such systems but only by the scope of the appended claims.

65 What is claimed is:

1. A wave retardation circuit comprising a plurality of four-terminal networks in sequence, one of said networks having a phase constant which increases less rapidly than the wave frequency, and the others of said networks consisting of similar ladder-type broad-band wave filter sections adapted to transmit freely wave frequencies below a critical value, the component elements of said filter sections being so proportioned that the resultant phase constant of the retardation circuit is substantially constant for a wide range of frequencies.

70 2. A wave retardation network comprising two four-terminal networks connected in sequence, the wave retardation interval of one of said networks diminishing as the wave frequency increases, and the other of said networks consisting of a ladder-type broad-band wave filter section adapted to transmit freely waves of frequencies less than a critical value, said filter section being proportioned to have a retardation interval which varies in a complementary manner to that of said first mentioned network whereby the wave retardation interval of said retardation section is made substantially constant for a wide range of frequencies.

3. A wave retardation network comprising a lattice type four-terminal network having simple inductances in the series branches and simple capacities in the shunt branches thereof, and a ladder type four-terminal network comprising two series inductances and a shunt capacity connected to the junction point thereof, the product of the sum of the inductances and the sum of the capacities of said lattice section being substantially equal to 0.63 times the product of the total inductance and the capacity of said ladder section.

4. A wave retardation network comprising a lattice type four-terminal network having simple inductances in the series branches and simple capacities in the shunt branches thereof, and a ladder-type four-terminal network comprising two series inductances and a shunt capacity connected to the junction point thereof, the product of the sum of the inductances and the sum of the capacities of said lattice section being substantially equal to 0.63 times the product of the total inductance and the capacity of said ladder section, and the iterative impedance of said lattice and said ladder sections being substantially equal for a wide range of frequencies.

5. A wave retardation network comprising a lattice type four-terminal network having simple inductances in the series branches and simple capacities in the shunt branches thereof, and a ladder-type four-terminal network comprising two series inductances and a shunt capacity connected to the junction point thereof, and the ratio of the total inductance to the total capacity in said lattice section being approximately equal to 0.8 of the corresponding ratio in said ladder section.

In witness whereof, I hereunto subscribe my name this 13th day of January A. D., 1925.

KENNETH S. JOHNSON.
